(57) **CLAIM**

We claim the ornamental design for a socket, as shown and described.

DESCRIPTION

FIG. 1 is a top, front and left perspective view of a socket showing our new design;

FIG. 2 is a bottom, rear and right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion 9 of FIG. 1;

FIG. 10 is an enlarged view of a portion 10 of FIG. 1;

FIG. 11 is an enlarged view of a portion 11 of FIG. 2; and,

FIG. 12 is an enlarged view of a portion 12 of FIG. 2.

In the drawings, the shorter and lighter broken lines are for the purpose of illustrating portions of the socket. The longer and darker broken lines are for the purpose of showing boundaries around the enlarged portions of the design. The broken lines form no part of the claimed design.
